US0D1090578S

(12) **United States Design Patent** (10) Patent No.: **US D1,090,578 S**
Chisena et al. (45) Date of Patent: ** Aug. 26, 2025

(54) **DISPLAY SCREEN WITH GRAPHICAL USER INTERFACE**

(71) Applicant: **Amplitude Vascular Systems, Inc.**,
 Boston, MA (US)

(72) Inventors: **Robert Chisena**, Boston, MA (US);
Theodore Kostopoulos, Boston, MA (US); **Elizabeth Peer Stegner Patton**, Skaneateles, NY (US)

(73) Assignee: **Amplitude Vascular Systems, Inc.**,
 Boston, MA (US)

(**) Term: **15 Years**

(21) Appl. No.: **29/905,452**

(22) Filed: **Oct. 20, 2023**

(51) LOC (15) Cl. **14-04**

(52) U.S. Cl. USPC **D14/486**

(57) **CLAIM**

The ornamental design for a display screen with graphical user interface as shown and described.

DESCRIPTION

The FIGURE is a front view of a display screen with graphical user interface.

In the drawing, the outer broken lines depict the environment and display screen and form no part of the claimed design. The remaining broken lines depict portions of the graphical user interface that form no part of the claimed design.
